CABLE SECURING STRAP

Lyle H. Mathews, 917 N. College Drive,
Santa Maria, Calif. 93454

Filed June 23, 1975, Ser. No. 589,615

Term of patent 14 years

Int. Cl. D9—06

U.S. Cl. D9—252

FIG. 1 is a right side perspective view of a cable securing strap showing my new design;

FIG. 2 is a left side elevation view thereof;

FIG. 3 is a bottom plan view thereof;

FIG. 4 is a rear elevation view thereof; and

FIG. 5 is a left side elevation view thereof with the strap in a cable securing position.

I claim:

The ornamental design for a cable securing strap, as shown.
